ATTORNEYS

UNITED STATES PATENT OFFICE.

SOL GARFUNKEL, OF UTICA, NEW YORK.

CEILING ELECTRIC-LIGHT FIXTURE.

1,331,494.

Specification of Letters Patent. Patented Feb. 24, 1920.

Application filed July 20, 1917, Serial No. 181,705. Renewed December 1, 1919. Serial No. 341,796.

To all whom it may concern:

Be it known that I, SOL GARFUNKEL, a citizen of the United States, and a resident of Utica, in the county of Oneida and State of New York, have invented certain new and useful Improvements in Ceiling Electric-Light Fixtures; and I do hereby declare that the following is a full, clear, and exact description thereof, which will enable others skilled in the art to which it appertains to make and use the same, reference being had to the accompanying drawings, and to the reference-numerals marked thereon, which form part of this specification.

15 My present invention relates to a ceiling electric light fixture of the direct lighting type as distinguished from the indirect or semi-indirect types in that the rays of light are directed outwardly and downwardly instead of upwardly. My invention also relates more particularly to the type of electric light fixtures where a shade is placed about the electric lamp in order to shade the eyes from the intense rays of light coming from 20 the strong electric lamps commonly utilized, and generally to diffuse the light and produce the desired so-called day-light effect. Fixtures embodying my invention are particularly adapted for use in commercial 25 places such as stores, offices and public buildings, but may be also used as ceiling lights in dwellings. While the fixture herein described will ordinarily have a diffusing shade of opalescent or other translucent 30 characteristics, the fixture may be provided with a clear shade if desired.

The general purpose of my present invention is to provide a new and improved form of ceiling electric light fixture of the general 35 type mentioned.

40 A further purpose is to provide an article of the class described that is very simple in construction and arrangement whereby the fixtures may be manufactured at a very reasonable cost and may be quickly assembled 45 and readily placed in position upon the ceiling by men having no special training.

50 A further purpose is to provide a ceiling electric light fixture wherein the fixture is of such form and is so placed bodily close to the ceiling that there is no opportunity for dust or other foreign matter to collect within

the shade or within or upon the reflector or upon the electric lamp or upon the member which depends from the ceiling to support 55 the fixture as a whole. In other words I provide a ceiling fixture of such form that the fixture is entirely inclosed from the outward periphery of the downward facing shade entirely up to the ceiling. 60

A further purpose is to provide an electric light fixture having a casing closely connected to the periphery of the shade and extending therefrom upward to the ceiling and entirely inclosing the fixture in a substantially 65 dust-proof manner.

Another object of this invention is to provide a fixture of the class described having its parts of such form and coöperation with each other that the parts may be readily 70 placed in position in a most convenient manner whereby the shade, the electric lamp, the electric lamp socket and the reflector may be successively removed without interfering with the rest of the fixture in order to be 75 cleaned, repaired or replaced as needed.

A further object of this invention is to provide a fixture of the type outlined wherein the whole fixture is conveniently supported from or assembled upon one common 80 supporting member which is adapted to be attached to the ceiling, said supporting member being entirely inclosed and concealed when the fixture is assembled.

Further purposes and advantages of my 85 invention will appear from the specification and claims herein.

Figure 1 is a side elevation of a ceiling electric light fixture embodying my invention.

Fig. 2 is an inverted plan view of the same or the fixture as seen from below.

Fig. 3 is a plan view of the same fixture or the fixture as seen from above.

Fig. 4 is a vertical sectional view on 95 line 4—4 of Fig. 3 but on an enlarged scale and with the electric lamp socket and most of the supporting member shown in side elevation.

Referring to the drawings in a more particular description, it will be seen that there is provided a supporting member 6 of any desired form, whereby said member may be affixed to the ceiling and form the means of

supporting the rest of the fixture and preferably form a part of the electrical connection to the lamp. A convenient form of such supporting member is that shown in the drawings wherein the supporting member 6 is provided with an upper screw-threaded portion 7 adapted to be screwed into a corresponding screw-threaded aperture 8 in a ceiling box or plate 9 suitably 5 fastened in or to the ceiling 30. Closely below the screw-threaded portion 7 the supporting member 6 is provided with a transversely extending aperture 10 which connects with a downwardly extending opening 11, into which fits preferably with screw-threaded engagement the head end 12 of the lower part 13 of the general supporting member 6. As the two parts of the supporting member 6 are brought together 10 they engage and hold in position a spider-like frame composed of outwardly extending arms 14, said frame being provided with a central aperture through which projects the upwardly extending head end 12 of the 15 lower part 13 of the supporting member 6. It will be understood of course that these details of construction are simply a convenient and the preferred way of making the supporting member and that said details 20 of construction may be modified if desired, the essential part being that the supporting member be adapted to be readily attached to the ceiling, provide support for the rest of the fixture and have its lower part 25 adapted to form part of the electrical connection of the fixture.

The lower part 13 of the general supporting member 6 is adapted to form part of the means for supporting the reflector 15 which 30 extends from said portion 13 outwardly and downwardly at the desired angle and to the desired extent. The member 13 is also a part of the electrical connection to the incandescent electric lamp 16 placed within 35 the reflector 15, said member 13 being of such construction as to receive thereinto either the plug end of an electric socket 17 or the plug of an electric lamp direct if so desired. As shown in the drawings the 40 member 13 has at its lower end an upwardly extending aperture to receive the plug 18 of the electrical socket 17. Preferably also the electrical socket 17 is adapted to form with the member 13 the means for supporting 45 and holding in place the reflector 15. This may conveniently be done by having said socket 17 provided with an outwardly extending and upwardly facing shoulder 19 at the bottom of the plug portion 18 upon 50 which the reflector rests when the plug is screwed or otherwise fastened up into position in the member 13 through the usual central opening in the reflector 15. Into the electrical socket 17 is placed the desired 55 incandescent electric lamp 16. If desired,

it is obvious that a multiple socket may be used in place of the single lamp socket shown in the drawings and thus provision may be made for several electric lamps in a fixture instead of the one shown.

Electrical connection is made in any well-known way through the member 13 by means of wires 20 and 21 extending down as from the ceiling box 9 through the transverse opening 10 and then down through the central aperture provided in the upwardly extending head 12 of the part 13.

Below the electrical lamp 16 is supported the shade 22, which as already stated will usually be of opalescent or some special form of translucent material; but may as far as the construction of my electric light fixture is concerned be of clear or transparent material. The shade 22 may be of any desired shape but will preferably be of such form and proportions and so placed relative to the electric lamp 16 and the reflector 15 as to direct the light outwardly and downwardly instead of upwardly. From the periphery of the shade 22 and united thereto by a substantially dust-proof joint as at 23 there extends upwardly to the ceiling a casing 24 of any desired material and form, but entirely inclosing the rest of the fixture from the shade 22 up to the ceiling. In the drawings 90 I have shown one way of supporting and connecting the shade 22 and casing 24 together and to the fixture, but it will be understood that these means may be modified very greatly and still have the resulting 95 construction within the spirit of my invention and within the claims hereinafter set forth.

The means I have shown as provided for supporting the shade 22 and casing 24 comprises the arms 14 projecting outwardly from the general supporting member 6 to the casing 24 and thereto secured as by means of screws or other fasteners 25. The shade 22 is secured immediately below and 100 suspended from the casing 24 as by means of a ring 25 angular shaped in cross-section and having its vertical web 26 secured to the lower portion of the casing 24 as by means 105 of screws 27, while the horizontal web 28 of said ring extends inwardly below the periphery of the shade 22, thus supporting said shade and holding it securely in position and also effecting a substantially dust-proof 110 joint between said shade and the casing.

It will now be seen that I have provided a ceiling electric light fixture which is new and improved in its general construction and combination of parts and which is very simple, practical and efficient. It will be 115 noted particularly that the electric light fixture herein described is free from the trouble common heretofore of dust, dirt, insects and other foreign matter gathering upon the upper side of the shade or upon the 120

lamp or upon either the upper or the lower surface of the reflector or upon the means used to support the fixture from the ceiling. This advantage results from having an encircling casing inclose the entire fixture from the periphery of the shade right up to the ceiling. This is an advantage both as to cleanliness and appearance and also as to real lighting efficiency of the fixture. It is known that where dust, dirt and other foreign substances gather upon a shade located below an electric lamp said foreign matter soon becomes affixed to the surface of the shade so that it cannot be readily cleaned off. Even where this dirt or other foreign matter does not become burned on to the shade it greatly reduces the amount of light passing through the shade until said material is removed. On account of the position and arrangement of most ceiling electric light fixtures there is so much difficulty in cleaning them from gathering dirt that the cleaning process is neglected or done only very occasionally. It will therefore be seen that my dust-proof fixture is a decided advantage over those heretofore commonly used.

It will be seen also that in my construction all exterior surfaces may be made to face downward or downward and outward and never upward. This arrangement of exterior surfaces affords practically no lodgment for dust and dirt and also renders the surfaces easy of access for cleaning.

What I claim as new and desire to secure by Letters Patent is:

1. In a ceiling electric lamp fixture, a member depending from a ceiling constituting a support for an electric lamp and an inclosing fixture, said fixture comprising a casing engaging the ceiling, a support for the casing, means for connecting said support and member, a reflector carried by the member, a shade, and means for connecting the shade and casing.

2. In a ceiling electric lamp fixture, a member depending from a ceiling constituting a support for an electric lamp and an inclosing fixture, said fixture comprising a casing engaging the ceiling, a support for the casing, means for connecting said support and member, a reflector carried by the member, a shade, and a member secured to the casing and engaging the shade for supporting said shade.

3. In a ceiling electric lamp fixture, a member depending from the ceiling constituting a support for an electric lamp and an inclosing fixture, said inclosing fixture comprising a casing extending from the ceiling, a support for the casing, means for connecting the support to the member, a reflector connected to the member below the support, and a shade below the reflector and means whereby the shade is carried by the casing.

4. In a ceiling electric lamp fixture, a member depending from the ceiling constituting a support for an electric lamp and an inclosing fixture, said inclosing fixture comprising a casing extending from the ceiling, 70 a spider carried by the member and attached to the casing, a reflector connected to the member below the support, and a shade below the reflector and means whereby the shade is carried by the casing. 75

5. In a ceiling electric light fixture the combination of a supporting member adapted to be secured to the ceiling and to receive therebelow an electric socket, a reflector extending downwardly and outwardly from 80 the supporting member, an electric socket within the reflector secured to the supporting member, an incandescent electric lamp secured to said socket, a shade supported beneath the lamp and a casing extending from 85 the edge of the shade upwardly to the ceiling and inclosing the entire fixture above the shade.

6. In a ceiling electric light fixture the combination of a supporting member adapted to be secured to the ceiling and to receive therebelow an electric socket, a reflector extending downwardly and outwardly from 90 the supporting member, an electric socket within the reflector secured to the supporting member and holding the reflector in position, an incandescent electric lamp secured to said socket, a shade supported beneath the lamp and a casing extending from the edge 95 of the shade upwardly to the ceiling and inclosing the entire fixture above the shade. 100

7. In a ceiling electric light fixture the combination of a supporting member adapted to be secured to the ceiling and to receive therebelow an electric socket, a reflector extending downwardly and outwardly from 105 the supporting member, an electric socket within the reflector secured to the supporting member, an incandescent electric lamp secured to said socket, a shade supported beneath the lamp upturned at its edge to substantially the edge of the reflector and a casing extending from the edge of the shade upwardly to the ceiling and inclosing the entire fixture above the shade. 110

8. In a ceiling electric light fixture the combination of a supporting member adapted to be secured to the ceiling and to receive therebelow an electric socket, a reflector extending downwardly and outwardly from 120 the supporting member, an electric socket within the reflector secured to the supporting member, an incandescent electric lamp secured to said socket, a shade supported beneath the lamp and a casing suspended 125 from said supporting member extending from the edge of the shade upwardly to the ceiling and inclosing the entire fixture above the shade.

9. In a ceiling electric light fixture the 130

combination of a supporting member adapted to be secured to the ceiling and to receive therebelow an electric socket, a reflector extending downwardly and outwardly from the supporting member, an electric socket within the reflector secured to the supporting member, an incandescent electric lamp secured to said socket, a shade sup-

ported beneath the lamp and a casing extending from the edge of the shade upwardly and outwardly to the ceiling and enclosing the entire fixture above the shade. ¹⁰

In witness whereof I have affixed my signature, this 6 day of July, 1917.

SOL GARFUNKEL.
